SHOE SOLE FITTING MACHINE

Lewis J. Bazzoni, Swampscott, Mass., assignor to
 United Shoe Machinery Corporation, Paterson,
 N. J., a corporation of New Jersey

Application October 18, 1935, Serial No. 45,638

16 Claims. (Cl. 12—17)

This invention relates to shoe sole fitting machines and is herein shown and described as embodied in a machine arranged to receive and feed a died out or rounded sole blank automatically past a cutter which in a single operation performed progressively around the sole reduces or bevels the marginal portion of the sole and produces a suitably roughened surface for the reception of sole attaching cement.

10 It is an object of the invention to provide such a machine as that indicated above in which the entire cutting and roughing operation is performed by a single tool so constructed and arranged that one degree of reduction or bevel may be produced around the forepart of the sole and a different degree along the shank portion thereof, the changes being made automatically without the necessity of any attention or manipulation upon the part of the operator.

15 A further object is to provide an improved and simplified form of sole feeding mechanism which will feed the marginal portion of the sole accurately and uniformly past the operating position of the tool regardless of the size or shape of the sole.

20 A still further object of the invention is to provide an improved form of tool which will accurately and cleanly bevel the sole margin and in the same operation produce a roughened surface for the reception of sole attaching cement.

25 With the above and other objects in view, a feature of the invention consists in the combination with a work support, such as a table having a sole engaging surface, and a sole roughing cutter supported in a mounting which is angularly variable or tilttable with respect to the work support to permit the angular relation between the cutter and the work supporting surface to be changed. In the illustrated machine the tool consists of a rotary coarse-toothed saw-like cutter mounted in a tilting carrier having manual means for varying the degree of tilt of the carrier relatively to the work supporting table, to determine at will the degree of bevel to be formed upon the

30 margin around the forepart of the sole and automatic means for changing the tilt of the cutter when the shank portion of the sole is reached in order to provide a greater degree of bevel along the shank than around the forepart.

35 The automatic change in the tilt of the cutter is preferably controlled by a characteristic of the sole itself and in the machine shown herein the control is electrical in that an appropriately located protuberance upon the sole actuates a feeler

40 which automatically closes an electric circuit con-

taining an electro-magnet which operates mechanism for changing the tilt of the cutter.

For determining the path of feed of the sole edge there may be provided an edge gage arranged above the work supporting table to cooperate with a tilted feeding disk engaging the sole margin near the edge gage, said disk having upon one of its faces a spiral sole feeding lip and being rotated in a direction to cause the edge of the sole to be held against the edge gage while it is being fed progressively past said gage.

These and other features of the invention, as well as benefits to be derived from the use thereof, will be better understood and appreciated from the following detailed description of the one embodiment thereof, to be read in connection with the accompanying drawings in which—

Fig. 1 is a left-hand end elevation of the machine;

Fig. 2 is a view partly in front elevation and partly in vertical section;

Fig. 3 is a plan view, mostly in horizontal section, of the cutter-tilting mechanism;

Fig. 4 is a view partly in elevation and partly in vertical section of the sole feeding device;

Figs. 5, 6 and 7 illustrate the cutter mounting and tilting mechanism with the axis of the cutter at different angles;

Fig. 8 shows the cutter mounting in vertical section;

Fig. 9 is a plan view of the sole feeding disk;

Fig. 10 is an elevation of a detail of the cutter tilting adjustment;

Figs. 11, 12 and 13 show details of the electromagnetic control for the cutter-tilting mechanism;

Fig. 14 is a diagram of the electric circuits;

Fig. 15 is an angular view of the forepart portion of a sole ready to be operated upon by the machine;

Fig. 16 is a diagrammatic plan view illustrating successive stages in the operation upon a sole, and

Fig. 17 is an angular view of a finished sole produced by the machine.

Referring now to the drawings, 20 indicates a frame or housing in which is mounted a base plate 22 to which is bolted an electric motor 24 to furnish power for operating the machine.

Secured to the shaft of the motor is a pinion 26 which transmits power through an idle gear 28 to a gear 30 mounted upon a countershaft 32 which extends through a frame 20 and has secured to its other end a grooved pulley 34. The pulley 34 is connected by a belt 36 running over a pair of idle pulleys 38 to a grooved pulley 40 secured by a

set screw 42 to a short shaft 44 (see Fig. 8) which has at its lower end a ball thrust bearing 46 adjustable axially of the shaft by a screw 48 locked in adjusted position by a lock nut 50.

5 The shaft 44 rotates in upper and lower ball bearings 52, 54 and has mounted at its upper end a coarse-toothed saw-like cutter 56 secured to the shaft by a screw 58. The ball bearings 52, 54 are mounted in holders 60, 62 formed in the forked 10 end of a tilting carrier 64 which is hung upon pivots 66, 68 arranged to swing in the ends of a short stationary shaft 70 secured in the underside of a horizontal work supporting and guiding table 72 supported by upright posts 74. The 15 axis of the cutter shaft 44 is disposed at right angles to the axis of the shaft 70 and the latter is angularly related to the upper work supporting surface of the table 72, with the result that the cutter 56 and its shaft are tilted longitudinally of the table. By reason of the pivotal mounting 66, 68 of the cutter carrier 64 the carrier together with the cutter and cutter shaft sustained thereby can be variably tilted transversely of the table 72. It will thus be seen that the cutter axis is tilted relatively to the table in two directions at right angles to each other. The purpose of the longitudinal tilting is to provide clearance between the sole and all of the cutter except that small portion of its periphery which is operating upon the work at any given instant and the purpose of the transverse tilting is to produce a beveled cut upon the sole margin, the degree of bevel being determined by the amount of transverse tilt given to the cutter.

20 35 The transverse tilt of the cutter is determined and varied both manually and automatically. The mechanism for manual adjustment, which ordinarily determines the angle of the bevel formed around the forepart of the sole, comprises 40 a knob 76 secured to the end of a rod 78 mounted to rotate in a bearing 80 formed upon the outside of the ball bearing holder 62. Secured to the opposite end of the rod 78 is a disk 82 (see Figs. 2 and 10) provided with a series of holes 45 84 so arranged that any one of them can engage with a stationary pin 86. A pinion 88 is also secured to the rod 78 and is mounted to turn in a bearing 90 formed in the carrier 64. A rack 92 (Fig. 5) is mounted to slide in a guideway 94 50 so arranged that the rack is held continuously in mesh with the pinion 88. Screwed into the rack 92 is a pin 96 which is connected by a link 98 surrounded by a spring 100 to a pin 102 adjustably threaded into the upper end of a lever 55 104 which is mounted to swing about a stationary pivot 106 in a manner to be described in detail hereinafter.

The rod 78 is surrounded by a spring 108 which tends to engage the disk 82 with the pin 86 but 60 by pulling the rod to the left, as viewed in Fig. 2, it may be turned to rotate the pinion 88 along the rack 92. Assuming the lever 104 to be stationary when this adjustment is changed the rack 92 will also be stationary and the rotation of 65 the pinion 88 will cause the transverse tilt of the cutter about the axis of the shaft 70 to be varied. A graduated scale 110 secured to the holder 62 cooperates with a stationary pointer 112 to indicate the amount of transverse tilt of 70 the cutter, the scale being shown as graduated in irons to indicate the amount of reduction to be produced in the thickness of the sole edge.

The stationary pivot 106 for the lever 104 is mounted in the wall of a housing 114 which contains the tilt controlling apparatus and which is

best illustrated in Figs. 2 and 3. The center of the lever 104 is pivoted at 116 to one end of a connecting rod 118 (Figs. 3 and 5) the opposite end of which is formed as a circular eccentric strap 120 embracing an eccentric 122 which is 5 radially adjustable upon a hollow shaft 124 rotatable in a bearing 126 sustained by the housing 114.

The eccentric 122 is slotted at 128 to cooperate with a flattened portion 130 of the shaft 124, the eccentric being forced to rotate with the shaft but being slidably adjustable radially of the shaft, for the purpose of varying the throw of the eccentric, from the position shown in Fig. 5 where the eccentric is concentric with the shaft to the 15 position of maximum eccentricity shown in Fig. 6. For the purpose of securing this adjustment there is mounted in the eccentric a pin 132 carrying a roll 134 which engages in a spiral slot 136 formed in a face of a disk 138 journaled to rotate upon the shaft 124. The disk 138 carries a spring pressed detent 140 which is engageable in any one of a series of depressions 142 in the adjacent face of a disk 144 formed upon the end of the shaft. It will be apparent from the foregoing that rotation of the disk 138 will adjust the eccentric 122 transversely of the shaft 124 and a stationary pointer 146 cooperating with numbers 148 corresponding to the depressions 142 will indicate the amount of such adjustment. The 20 graduations or numbers 148 may be so selected as to designate the numbers of irons difference in the thickness of the sole edge which will be produced by the tilting of the cutter 56 effected by 25 the throw of the eccentric 122.

The shaft 124 is rotated by the driven member 150 of a clutch of peculiar construction comprising a driving member 152 pinned to a shaft 154 and an intermediate member 156 which is rotatable upon the shaft 154 but is in frictional engagement with the driving member 152. The driven member 150 is pinned upon a rod 158 which is slidable axially through the hollow shaft 124 and its hub portion 160 is formed for interlocking driving engagement with a hub projecting from the face of the disk 144, as shown in Figs. 2 and 3. This construction permits the rod 158 and the driven clutch member 150 to move axially of the shaft 154 but maintains rotary driving engagement between the clutch member 150 and the hollow shaft 124.

The shaft 154 is journaled in bearings 164 in a gear box 166 which is supported by the machine frame 20 and the shaft has pinned to it a gear 168 which meshes with a pinion 170 keyed to a sleeve 172 which is in turn pinned to a shaft 174 to which is affixed a driving gear 176. The gear 176 meshes with an idle gear 178 which is driven by the pinion 30 upon the counter shaft 32, the shafts 174 and 154 rotating continuously whenever the motor 24 is running.

As already intimated, the function of the eccentric 122 is to change the tilt of the cutter 56 about the axis 70 and the apparatus in the housing 114 for controlling this operation will be described in detail hereinafter but, inasmuch as the operation of the said apparatus is determined by a characteristic of the sole blank being fed past the cutter, the sole feeding mechanism will be described next.

Secured to the continuously running sleeve 172 on the shaft 174 is a gear 180 which meshes with a pinion 182 affixed to an inclined shaft 184, to the upper end of which is pinned a feed disk 186 having a spiral work feeding lip 188 upon its 75

upper face. The lip 188 is sharp so that it will cut into the sole and obtain sufficient grip on the sole to feed it along as the disk is rotated. The shaft 184 is slideable through bearings 190, 192 and its lower end is rounded, as shown at 194, and stepped in a thrust bearing 196 supported by a spring 198 which tends to force the shaft 184 and the feed disk 186 upward into engagement with the sole but is capable of yielding to accommodate irregularities in the thickness of the sole material.

Above the feed disk 186 is a presser foot 200 carried by a slide 202 which is vertically adjustable for soles of different thicknesses, being held in adjusted position by a bolt 204 passing through 15 a slot 206 in a stationary supporting bracket 208. The adjustment is indicated by graduations 210 upon an adjustable polygonal stop member 212 at the top of the bracket. The presser foot 200 is normally stationary and serves to hold the sole 20 down against the upward thrust of the feed disk 186 and the cutter 56.

The shaft 184 is inclined both transversely and longitudinally of the work table 72 to such an extent that only a segment of the lipped portion 25 of the feed disk 186 projects above the sole supporting surface of the table, where it can engage the sole, and the same is true as to the operative segment of the cutter 56.

The direction of rotation of the shaft 184 is indicated by an arrow in Fig. 1 and the corresponding direction of rotation of the feed disk 186, which is secured to the said shaft, is indicated by arrows in Figs. 9 and 16. By referring to Figs. 2 and 16 it may be seen that, since only the upper 35 right hand portion of the feed disk is exposed above the table 72 to engage the sole, the progression of the teeth formed by the sharp edge of the turning spiral lip 188 will cause the sole to be fed toward the right, toward the cutter 56, in 40 a direction which is approximately radial with respect to the feed disk, the tendency of the sole to whirl tangentially of the disk being overcome by engagement of the sole edge with a stationary edge gage or abutment 308. The operation of 45 the cutter removes from the sole any marks which have been made upon it by the lip 188.

Referring now to Figs. 15 and 17, the sole blank 214 is provided, at the points on its margin where the change in edge thickness is to occur, with 50 humps or protuberances 216, 218 which may conveniently be formed by forcing a pointed instrument into the edge of the sole. Referring now to Figs. 2 and 14, a feeler 220 which is mounted to move about a pivot 222 is arranged to engage the 55 margin of the sole in the path of movement of the protuberance 218 so that when the latter strikes the feeler the feeler will be swung upward about the pivot 222 and a contact arm 224 which extends upward from the feeler will be actuated to 60 close a pair of contact points 226, 228. The contact point 226 is connected to a wire 230 which is one of two wires constituting a source of supply of electric current; the other wire of the pair is shown at 232 in Fig. 14.

65 The contact point 228 is connected by a wire 234 to one end of an electro-magnetic solenoid 236 the other end of which is connected to the line wire 232. When the feeler 220 is lifted by the passage of the protuberance 218 under it the circuit containing the solenoid is closed momentarily at 226, 228 energizing the solenoid and causing it to draw in a sliding core 238 which operates the mechanism now to be described for changing the tilt of the cutter.

70 The solenoid core 238 is connected by link 240

(Fig. 3) to a lever 242 mounted to swing about a stationary pivot 244 and having rigid with itself an arm 246. A screw 248 threaded adjustably through the lever 242 bears against the end of the clutch shifting rod 158 which is held in engagement with the tip of the screw by a compression spring 260 surrounding the rod and retained thereon by a nut 262.

A disk 264 is keyed upon the hollow shaft 124 and outside of this disk is a ring 266 which is 10 capable of rotation through a limited angle relatively to the disk 264, a compression spring 268 being interposed to keep the parts normally in the relation shown in Fig. 13. The ring 266 has in its periphery two identical notches 270 which are diametrically opposite to each other and a spring pressed locking dog 272 is mounted in the housing 114 in position to engage in either of these notches. It will be apparent that when the locking dog is engaged in either of the notches 20 270 the shaft 124 will be locked against rotation, and the two notches are so arranged that when this occurs the eccentric 122 will be at one or the other of the limits of its horizontal 25 throw.

A pin 274 projects upward from the locking dog 272 in the path of a spring projected pawl 276 which is pivoted at 278 in the outer end of the lever arm 246. When the solenoid 236 is energized and draws in the core 238 the lever 242, 246 30 is swung counterclockwise, as seen in Fig. 3, causing the locking dog 272 to be retracted from one of the notches 270 and unlocking the ring 266 so that the shaft 124 can rotate. At the same time, the tip of the screw 248 moves the clutch shifting 35 rod 158 to the left, engaging the clutch 150, 156, 152 and starting rotation of the shaft 124. The pawl 276 quickly snaps by the pin 274 allowing the dog 272 to engage the periphery of the ring 266 and as soon as this ring and the shaft 124 have 40 made half a revolution the dog enters the second notch 270 stopping the rotation, the shock of the stop being cushioned by the spring 268 and, if necessary, slippage occurring between the driving member 152 and the intermediate member 45 156 of the clutch.

In order to maintain the circuit through the solenoid 236, which is closed only momentarily at the contacts 226, 228, there is provided a holding circuit which is controlled by the ring 266. 50 This holding circuit comprises a conductor 280 (Fig. 14), contacts 282, 284 and a conductor 286 connected to the supply wire 230. This holding circuit is normally open at the contacts 282, 284 but is closed as soon as the shaft 124 starts to 55 rotate and is kept closed through a half revolution of the shaft. For this purpose a bell crank lever movable about a pivot 286 has a depending arm 288 provided with a tappet 290 arranged to engage the periphery of the ring 266 when the ring is rotating but to lie in one of the notches 270 when the ring is stationary. The other arm 292 of the bell crank lever is angularly adjustable by means of a screw 294 and carries an abutment 296 arranged to press the contact 284 against the contact 282. The mechanical arrangement is 60 shown in Fig. 13 while Fig. 14 is merely a schematic circuit diagram.

When the shaft makes a half revolution and is stopped by the locking dog 272 the tappet 290 falls into the notch 270 which is not occupied by the locking dog, opening the holding circuit at the contacts 282, 284 and permitting the spring 260 to disengage the driving clutch and retract 70 the solenoid core 238 to its initial position. Each 75

half revolution of the shaft 124 tilts the cutter carrier one way or the other, either increasing or decreasing the angle of bevel of the cut upon the sole margin as the case may be.

5 The contact points 282, 294 are carried, respectively, by a pair of spring fingers 298 and 300 which are clamped between strips of insulating material 302 held together by a screw 304 threaded into a lug 306 projecting inward from the wall 10 of the housing 114.

The sole blank is guided in its movement relative to the cutter 56 by an edge gage 308 as shown diagrammatically in Fig. 16 where it may be observed that the direction of rotation of the 15 feed disk 186 is such as to force the edge of the sole continuously against the edge gage as the sole is fed past the cutter and in practice the component forces exerted upon the sole to hold it against the edge gage and to feed it along 20 are so related that the feeding and guiding of the sole are practically automatic, it being unnecessary for the operator to guide the sole by hand in its passage through the machine.

Reference to Fig. 5 shows how the cutter 56 will 25 produce no bevel upon the sole when both cutter-tilting adjustments are set at zero; Fig. 7 illustrates the production of a slight bevel suitable for the forepart of the sole such as would be produced by turning the adjusting knob 76 and 30 thereby tilting the cutter slightly; and Fig. 6 shows the steep bevel suitable for the shank portion of the sole produced by operation of the cutter-tilting eccentric 122 when adjusted for maximum throw.

35 Having described the invention, what is claimed as new and desired to be secured by Letters Patent is:

1. A machine for roughing the margins of unattached shoe soles, comprising, in combination, 40 a work support having a sole engaging surface, a sole roughing cutter constructed and arranged to operate upon a face of the sole, said cutter being disposed at an acute angle to said surface of the work support, and a cutter mounting which is 45 angularly variable with respect to the work support to permit the angular relation between the cutter and said surface to be changed.

2. A machine for roughing the margins of unattached shoe soles, comprising, in combination, 50 a work support having a sole engaging surface, a sole roughing cutter which is tiltable with respect to said surface, and means controlled by a characteristic of a sole upon the work support for tilting the cutter relatively to said surface.

55 3. A machine for roughing the margins of shoe soles, comprising, in combination, a work support having a sole engaging surface, a sole roughing cutter mounted in a carrier which is tiltable with respect to said surface, a feeler arranged adjacent to the work support in a position to engage 60 a sole thereon, and connections between the feeler and said carrier constructed and arranged to tilt the carrier when the feeler is engaged by a predetermined portion of the sole which differs from the remainder thereof.

65 4. In a machine for roughing the margin of a shoe sole, the combination of a sole guiding element, a sole roughing cutter mounted to tilt relatively to the sole guiding element, a feeler arranged to be engaged continuously by the sole, and electrical means controlled by the feeler for 70 tilting the cutter.

5. In a machine for reducing and roughing the margin of a shoe sole, the combination of a con- 75 cavo-convex circular saw-like cutting and rough-

ing tool, means for rotating said tool, and a sole guiding element disposed at the concave side of the tool and arranged to guide the marginal portion of a sole past the concave face of the tool in a plane at a small angle to the path of movement of the cutting teeth of the tool.

6. In a machine for reducing and roughing the margin of a shoe sole, the combination of a con- 10 cavo-convex circular saw-like cutting and roughing tool, means for rotating said tool, and means for feeding the marginal portion of the sole past the concave side of the tool in the path of movement of the cutting teeth thereof.

7. In a machine for roughing the margin of a shoe sole, the combination of a work supporting 15 table, mechanism for feeding a sole along said table, and a toothed tool mounted to rotate upon an axis which is tilted relatively to the table both in the direction of work feed and transversely thereto.

8. In a machine for roughing the margin of a shoe sole, the combination of a work supporting 20 table, mechanism for feeding a sole along said table, and a toothed tool mounted to rotate upon an axis which is tilted relatively to the 25 table to a fixed extent in the direction of work feed and to a variable extent in a direction transverse thereto.

9. A machine for operating upon the margins of shoe soles, comprising, in combination, a sole 30 support, a sole roughing and reducing cutter, means for moving a sole upon said support in a path such as to present the cutter to the sole progressively along one side of the shank, around the forepart and along the other side of the 35 shank, and means for changing the angle of presentation during the progressive operation.

10. A machine for operating upon the margins of shoe soles, comprising a sole support, a tiltable 40 cutter, means for feeding a sole over the support past the cutter, manual means for varying the tilt of the cutter as desired, and automatic means for changing the tilt of the cutter during the operation of the machine upon a sole.

11. A machine for operating upon the margins of shoe soles, comprising a sole support, a tiltable 45 cutter, manual means for varying the tilt of the cutter as desired, automatic means for changing the tilt of the cutter by a definite amount during the operation of the machine upon a sole, and manual means for varying the amount of change of tilt produced by said automatic means.

12. In a machine for operating progressively around the marginal portion of a shoe sole, a work support and guiding table and a sole feeding member comprising a disk having a sharp, 55 spiral work engaging and feeding lip upon its face.

13. In a machine for operating progressively around the marginal portion of a shoe sole, a work supporting and guiding table and a sole feeding member comprising a disk inclined relatively to the table and having upon its face a sharp, spiral work engaging and feeding lip.

14. In a machine for operating progressively around the marginal portion of a shoe sole, a work supporting and guiding table, an edge gage for determining the path in which a sole is to be fed, a sole feeding disk having a sharp, spiral work feeding lip which lies in a plane inclined to the table, and means for rotating the disk in a direction to hold the edge of the sole against the edge gage and to move the sole edge progressively past said gage.

15. In a machine for operating progressively 75

around the marginal portion of a shoe sole, a work supporting and guiding table, an edge gage above the table for determining the path in which a sole upon the table is to be fed, an inclined sole feeding disk a portion of which projects above the table adjacent to and beneath the edge gage, a spiral work feeding lip upon the disk, and means for rotating the disk in a direction to hold the edge of the sole against the edge gage and to move the sole progressively past said gage.

16. A machine for operating upon soles comprising cutting means arranged to reduce the

thickness of the margin of an unattached sole, means arranged to guide the sole by its perimeter, power driven feeding means arranged to present the sole progressively to said cutting means with a component of edgewise pressure, against said guiding means, a power driven start-and-stop mechanism arranged to alter the setting of said cutting means to regulate the angle of cut upon the work, and means arranged to be actuated by the work to control the regulatory operation of said start-and-stop mechanism.

LEWIS J. BAZZONI.
